SHADE-ROLLER.

1,373,641.

Specification of Letters Patent.

Patented Apr. 5, 1921.

Application filed June 24, 1918. Serial No. 241,471.

To all whom it may concern:

Be it known that I, FRANK E. WILLIAMS, a citizen of the United States, residing at Alhambra, in the county of Los Angeles and State of California, have invented new and useful Improvements in Shade-Rollers, of which the following is a specification.

This invention relates to shade rollers, and more particularly to shade rollers of the spring actuated type wherein a torsion spring is employed to rotate the roller and so roll up the shade and against which spring action the shade is drawn in the lowering and unrolling of the same. The invention has for its object to provide a shade roller of the general nature stated which will be free from the disadvantages of such rollers as ordinarily constructed, in that it is more positive in action, may be adjusted to a nicety and will automatically be brought to a stop in case of accidental release during the manipulation of the same; these desiderata are not met with in ordinary shade roller practice, as may be readily demonstrated by attempting to closely adjust the lower margin of a shade mounted upon an ordinary or standard roller, as to the case of nicety of adjustment, and by releasing the grip on the shade during the unrolling or the rolling up action, as to the automatic stopping of the roller; in the latter case, in ordinary practice, it will be found that the shade will rush to completely rolled up position when released, and when stopped at all, such stoppage will be due to either the completely unwound condition of the spring or to stoppage by impact of lower marginal shade portions as they strike and lodge in the crotch formed by the roller and the window casing upon which the shade is mounted; the non-desirability of such impact is obvious.

In accordance with the present invention, a spring actuated roller adapted to have a shade secured thereto and wound thereupon may be provided and such roller and its spring may resemble the conventional type to a certain extent in that the roller is rotatable about an internally disposed fixed rod to which one end of the spring is secured, and about which the spring is coiled, the other end of the spring being secured in such manner to the roller that the same may be rotated thereby; however, in the present invention, an engagement means, preferably in the form of a pawl, is provided in conjunc-

tion with the fixed rod and in position to be acted upon and against by co-acting means, preferably in the form of two series of bars carried by the roller. The pawl being preferably mounted for oscillation about a fixed pivot is adapted for engagement with either series of bars, and is projected into one or the other of such series of bars to stop the roller, or into an annular free space between the two series of bars, according to the rate of speed or rotatory motion of the roller. The pawl is adapted for locking engagement with the bars only to prevent rotation thereof in a certain direction, namely, in the direction of movement directly caused by the spring, so that the roller may be freely rotated in unrolling the shade, but must be released or fed back to the roller at a speed intermediate the slow rate of speed at which a bar of one series would be caught by the pawl, and the high rate of speed at which a bar of the other series would be caught by the pawl. The pawl is preferably arranged to fall into the slow speed series of bars by gravity, and such bars are preferably each of such form that at the intermediate speed of roller rotation under impulse of the spring the pawl is projected upwardly into the annular space as each bar of the low speed series strikes it, so causing it to remain out of contact with the leading edge of the next succeeding bar of the slow speed series; the pawl however, at intermediate roller speed, falls onto such succeeding bar behind the leading edge thereof and is projected upwardly thereby onto the next succeeding bar. At relatively slow speed of roller rotation, such as is permitted by proper manipulation of the shade, the pawl falls downwardly so that a nose thereon enters the space between two bars of the slow speed series and contacts with the oncoming leading edge of a bar, so stopping the roller, the spring holding the bar and pawl nose in engagement. At high speed of roller rotation, as under impulse of the spring when unrestrained by manually holding the shade, or otherwise, a bar of the slow speed series will strike the pawl with such force that the same will be driven upwardly far enough to engage one of the bars of the high speed series and so lock the roller against further movement under urging of the spring until manually released by first pulling downwardly upon the shade.

With the above and other objects in view,

including relative simplicity and inexpensiveness in construction and organization coupled with reliability and serviceability, the invention consists in the novel and useful provision, formation, combination, association and relative arrangement of parts, members and features, all as hereinafter described, shown in the drawing and finally pointed out in claims.

10 In the drawing:

Figure 1 is a central longitudinal sectional view of a shade roller constructed and organized to embody the invention, the view being taken on the line x^1-x^1 , Fig. 4, and 15 looking in the direction of the appended arrows;

Fig. 2 is a transverse sectional view taken on the line x^2-x^2 , Fig. 1, and looking in the direction of the appended arrows;

20 Fig. 3 is a transverse sectional view taken on the line x^3-x^3 , Fig. 1, and looking in the direction of the appended arrows;

Fig. 4 is a view similar to Fig. 3, but with parts shown in other positions; and

25 Fig. 5 is a transverse sectional view taken on the line x^5-x^5 , Fig. 1, and looking in the direction of the appended arrows, parts being omitted for clearness of illustration.

Corresponding parts in all the figures are 30 designated by the same reference characters.

Referring with particularity to the drawing, in the embodiment of the invention therein shown, A designates a shade roller, B designates spring means therefor, C designates engagement means, and D and E designate, respectively, normal stop means and automatic stop means, either of which means may co-act with the engagement means C in motion checking action, according to the speed of roller rotation.

The roller A comprises a preferably wooden body portion 6 having a journal, not shown, at its one end and whereby such end may be rotatably supported in a bracket 45 in the usual manner, and having a longitudinal bore 7 extending inwardly thereof at its other end. The spring means B for actuating the roller is shown as comprising a helical torsion spring 8 having its one end 50 secured to a rod 9 which rod is disposed in the bore 7, and having its other end 8^b secured to a spring-clip 10 driven into the bore 7 at the bored end of the wooden body 6. The rod 9, spring 8 and clip 10 may be of 55 the well known standard type and the mode of securing the spring ends to the rod and clip may follow the usual practice, one end of the rod 9 being preferably inserted in the clip 10 which is formed to receive the same.

60 The engagement means C is shown as comprising an oscillatory pawl 11 mounted upon a supporting plate 12 as by means of a pivot 13. The pawl may be apertured at 11^a to receive the pivot and may be confined between the plate 12 and a head 13^a

on the pivot the pivot extending into and being riveted onto the plate 12 as at 13^b. The plate 12 is centrally apertured as at 12^a to receive the shank portion of a bracket-engaging member 14; such shank portion 70 comprises a stud 14^a fitted into the end of the rod 9 at the clip 10, and a tubular pivot portion 14^b fitted over the stud 14^a, the tubular pivot portion 14^b, the stud 14^a, the plate 12, and the rod 9 all being fixed and 75 held together when the parts are in proper assemblage; the stud 14^a is held to the rod 9 by a pin 14^c passed through an aperture 14^d provided in the rod and stud. The member 14 is formed at its outer end with 80 a flat portion 14^e adapted to be held in a vertical plane, and against rotation, in a standard bracket, a projection 14' indicating that the edge provided with such projection is to be the lower edge as the flat portion is inserted in the vertical slot usually provided in the standard bracket for the corresponding end of the shade roller. The pawl 11 at its free end is bifurcated to 85 provide a notch 11' so that the pawl is 90 adapted for engagement with bars of either the normal stop means or the automatic stop means.

The normal stop means D is shown as comprising a series of four bars 15 preferably formed integrally with and struck out from a plate 15^a and so providing a central aperture 15^b in the plate 15^a, which aperture accommodates the tubular pivot 14^b of the member 14, the inner surfaces of the bars 15 resting on such tubular portion 14^b and so rotatably supporting the plate 15^a and the wooden body 6 attached thereto, as will presently be described. The bars 15 are preferably arranged tangentially about the 105 pivot portion 14 and each may be arranged at right angles to adjacent bars, so together forming a sort of interrupted square, each bar extending from one corner of the square toward another corner but terminating in 110 a leading edge 15^b a short distance from such corner and so providing an interspace between adjacent bars into which a prong 11^b of the bifurcated end of the pawl may fall. The bars 15 extend across a pawl-space between the plate 12 and the plate 15^a and abut against a face of the plate 12 so 115 determining the width of such space, which is wide enough to permit free vertical movement of the pawl therein. The invention is 120 not limited to the specific form of the bars just described but their form may be infinitely varied both as to construction, surface angles, and otherwise to meet various requirements in practising the invention. 125

The automatic stop means is shown as comprising a series of bars 16 projecting across the space between the plate 12 and the plate 15 and over the peripheral margin of the plate 12 and are 130 preferably struck

up from the plate 15^a in a manner similar to the formation of the inner series of bars 15 of the means D but outwardly thereof, so providing for an annular space between 5 the two series, the pivot and pawl being accommodated in such space. The bars 16 preferably are arranged with their under surfaces inclined inwardly so as to present a leading edge 16^a to the pawl notch for engagement by the prong 11^c of the pawl 11, such prong 11^c entering one of the interspaces 16' between adjacent bars 16 when projected upwardly with sufficient force by 10 the bars of the inner series to raise the nose 15 of the pawl to the zone of the bars 16.

It will be understood that any desired 20 number of either the bars 15 or the bars 16 may be provided, the degree of roller rotation under the impulse of the spring before checking action may be had through either 25 of the checking or stop means C or D being directly dependent upon the number of bars in the respective series.

The spring attachment clip 10 is preferably 30 provided with a pair of oppositely disposed reduced tips 10^a and 10^b which are inserted through apertures in the plate 15^a and the tips 10^a and 10^b bent over against the forward face of the plate 15^a, channels 35 17 being provided in such face to accommodate the tips and prevent their interference with pawl action. An aperture to receive the pivot portion 14^b is provided centrally in the clip 10 and a washer 18 may be 40 clamped between the clip 10 and the back face of the plate 15^a. The parts thus being held in assemblage, the plate 15^a with its bars 15 and 16 is secured to the spring clip 10 which is in turn fitted into the bore 7 45 of the roller body, so uniting these parts for joint rotation. A ferrule 19 provided with an aperture 19^a through which the member 14 projects is fitted to the wooden roller body 6 in position to serve as a housing for the parts.

The operation, method of use and advantages of the invention will be readily understood from the foregoing description, taken 50 in connection with the accompanying drawing and the following statement:

A shade being secured at its inner end to the wooden roller body 6 and wound thereupon, the spring 8 put under tension, and the roller mounted in suitable brackets with 55 the member 14 and parts fixed thereto secured against rotation, the pawl pivot being so fixedly disposed at a point above the series of bars 15, the pawl nose will be held, due to gravitation, against one of the bars 60 15 of the inner or slow speed series. When the shade is unrolled in the usual manner as by drawing down on the lower marginal portion thereof, the pawl being cut away as 65 at 11^d on its under side, will be thrown out of the interspace between two bars and so

permit rotation of the roller body with its bars 15 and 16, the rotation being in the direction indicated by the curved arrow near Fig. 3. Upon drawing down the shade to the extent desired, it may be secured in its 70 position of adjustment by allowing it to slowly recede or roll up under the influence of the torsion spring until the pawl nose reaches an interspace between adjacent bars 15 and the pawl prong 11^b falls into such 75 interspace and the leading edge of a bar 15 is caught by the pawl nose so preventing further movement by the spring. As the motion of the pawl is entirely dependent upon the speed of rotation of the bars 15, 80 it may be caused to ride over each bar 15 and be projected vertically by each such bar as the inclined outer surfaces of succeeding bars impinge upon the pawl nose, each succeeding vertical projection of the pawl nose 85 enabling it to ride over the gap or interspace provided between adjacent bars 15 and so leap from bar to bar as long as supported by an intermediate speed of roller and bar rotation; this is the action of the 90 pawl during the rolling up action of the shade under the torque of the spring and when manipulated so as to be fed to the roller at a moderate speed only.

If, however, the shade is released at any 95 point in its travel and in a manner permitting the spring to transmit a rapid rate of rotation to the roller, a bar 15 violently striking the pawl nose will send it flying upwardly to the zone of the bars 16 and the 100 first of such bars 16 to present itself to the pawl nose will be caught thereby at its leading edge and further rotation prevented, so bringing the roller to a stop almost immediately after a free start, and avoiding the 105 damage and annoyance caused by the slamming and impact of shade parts incident to the use of the aforementioned ordinary forms of spring rollers.

It is manifest that many changes and departures from the disclosure herein may be made in adapting the invention to various requirements of use and service without departing from the spirit of the invention and the terms of the following claims.

Having thus disclosed my invention, I claim and desire to secure by Letters Patent:

1. A shade roller comprising a rotatable body member, a spring supporting rod extending into said body member and adapted 120 to be held against rotation, a spring connected with said body member and said rod, means for rotatably mounting said member, a series of elements rotatable with said body member and adapted for pawl actuation, a 125 pawl held against rotation with said body member and adapted to normally lie against elements of said series, and a second series of elements rotatable with said body member and against which the pawl is projected 130

by an element of said first named series at high rate of speed of body member rotation; said pawl engaging an element of said first named series to hold the body member 5 against rotation under influence of the spring at slow rate of speed of body rotation; and the leading and following edges of each of the elements of said first named series being disposed at different radial distances from the center of rotation.

2. A shade roller comprising a rotatable body member, a spring supporting rod extending into said body member and adapted to be held against rotation, a spring connected with said body member and said rod, means for rotatably mounting said body member, a series of elements rotatable with said body member and adapted for pawl actuation, a pawl held against rotation with said body member and adapted to fall under the influence of gravitation against said elements, and a second series of elements rotatable with said body member and against which the pawl is projected 25 by an element of said first named series at a high rate of speed of body rotation; said pawl engaging an element of said first named series to hold the body member against rotation under influence of the 30 spring at a slow rate of speed of body rotation; the elements of said first named series being each provided with a leading edge which is presented to the pawl in a plane lower than the following edge of the 35 element and whereby the pawl is impinged upon to project the same upwardly and so permit the introduction of the leading edges of successively presented elements of such series thereunder at a moderate speed of 40 body rotation.

3. A shade roller comprising a hollow rotatable body member, a spring supporting rod extending into said body member, a spring connected with said member and 45 said rod, means for rotatably mounting said body member, means whereby said rod may be held against rotation, an oscillatory pawl held against rotation about the axis of said body member, and a plurality of 50 series of pawl-engaging elements secured to said body member for rotation therewith; said pawl being adapted for engagement with the elements of one of said series as it falls under the influence of gravitation at a 55 slow speed of body member rotation to stop the body member and being adapted for engagement with the elements of the other series when impinged upon by the elements of the first series during high rate of speed 60 of body member rotation to stop the body member; and the leading and following edges of each of the elements of said first series being disposed at different radial distances from the center of rotation.

65 4. A shade roller comprising a hollow ro-

tatable body member, a spring supporting rod extending into said body member, a spring connected with said body member and said rod, means for rotatably mounting said body member, means for preventing rotation of the rod, a pawl mounted so as to be held against rotation with said body member, an inner series of pawl-engaging elements rotatable with said body member and between which the pawl is adapted to 70 fall and stop the body member when the body member rotates at slow speed under 75 influence of the spring, an outer series of elements rotatable with the body member and between which the pawl may be thrown by 80 the elements of the inner series impinging thereon at a high rate of speed of body member rotation under influence of the 85 spring so to stop the body member; and the leading and following edges of each of the elements of said inner series being disposed at different radial distances from the center of rotation.

5. A shade roller comprising a hollow rotatable body member, a spring supporting 90 rod extending into said body member, a spring connected with said body member and said rod, means for rotatably mounting said body member, means for preventing rotation of the rod, a pawl mounted so as to 95 be held against rotation with said body member, an inner series of pawl-engaging elements rotatable with said body member and between which the pawl is adapted to fall and stop the body member when the 100 body member rotates at slow speed under influence of the spring, an outer series of elements rotatable with the body member and between which the pawl may be thrown by 105 the elements of the inner series impinging 110 thereon at a high rate of speed of body member rotation under influence of the 115 spring so to stop the body member; the pawl-engaging surfaces of the inner series 120 of elements being so formed that at a moderate speed of rotation under the influence of the spring the pawl will be projected into but not across the space between the two series of elements by the impingement of successively presented elements of the inner series thereagainst so preventing the pawl 125 entering spaces between elements of the same series during such moderate speed of body rotation; and the leading and following edges of each of the elements of said inner series being disposed at different radial distances from the center of rotation.

In testimony whereof, I have signed my name to this specification in the presence of two subscribing witnesses.

FRANK E. WILLIAMS.
